(57) **CLAIM**

The ornamental design for a combination pool or spa skimmer as shown and described.

DESCRIPTION

FIG. 1 is a front, top, right perspective view of a combination pool or spa skimmer showing my new design; FIG. 2 is a front, bottom, right perspective view thereof; FIG. 3 is a rear, bottom, left perspective view thereof; FIG. 4 is another front, top, right perspective view thereof; FIG. 5 is a rear, top, left perspective view thereof; FIG. 6 is a front elevation view thereof; FIG. 7 is a rear elevation view thereof; FIG. 8 is a right side elevation view thereof, the left side being a mirror image thereof; FIG. 9 is a top plan view thereof; FIG. 10 is a bottom plan view thereof; FIG. 11 is a front, top, right perspective view thereof, showing the netting removed from the remainder of the combination pool or spa skimmer; FIG. 12 is a front, top, right perspective view thereof, illustrating a disclaimed variant netting removed from the remainder of the combination pool or spa skimmer; FIG. 13 is a rear, bottom, left perspective view thereof, showing the netting removed from the remainder of the combination pool or spa skimmer; and, FIG. 14 is a rear, bottom, left perspective view thereof, illustrating a disclaimed variant netting removed from the remainder of the combination pool or spa skimmer. The broken lines depict unclaimed features of the combination pool or spa skimmer that form no part of the claimed design.
